UNITED STATES PATENT OFFICE

ARTHUR KNAUER, OF WEST READING, PENNSYLVANIA, ASSIGNOR TO NARROW FABRIC COMPANY, OF WEST READING, PENNSYLVANIA, A CORPORATION OF PENNSYLVANIA

DESIGN FOR AN ELASTIC FABRIC

Application filed September 28, 1932. Serial No. 45,108. Term of patent 14 years

To all whom it may concern:

Be it known that I, ARTHUR KNAUER, a citizen of the German Republic, residing at West Reading, in the county of Berks and State of Pennsylvania, have invented a new, original, and ornamental Design for an Elastic Fabric, of which the following is a specification, reference being had to the accompanying drawing forming part thereof.

Fig. 1 is a front view of the elastic fabric showing my novel design.

Fig. 2 is a view showing the reverse side of the elastic fabric shown in Fig. 1.

In the views the fabric is shown approximately actual size.

As shown in the drawing, the fabric exhibits specifically different design motifs when viewed from opposite sides thereof.

I claim:

The ornamental design for an elastic fabric as shown and described.

In testimony whereof I affix my signature.

ARTHUR KNAUER.
